(57) **CLAIM**

The ornamental design for a detachable sanitary handle for forearm lifting of refuse/recycle bin lids, as shown and described.

DESCRIPTION

FIG. 1 is an upper front-left perspective view of the detachable sanitary handle for forearm lifting of refuse/recycle bin lids.

FIG. 2 is a lower rear-right perspective view of the detachable sanitary handle for forearm lifting of refuse/recycle bin lids.

FIG. 3 is a front view of the detachable sanitary handle for forearm lifting of refuse/recycle bin lids.

FIG. 4 is a rear view of the detachable sanitary handle for forearm lifting of refuse/recycle bin lids.

FIG. 5 is a left side view of the detachable sanitary handle for forearm lifting of refuse/recycle bin lids.

FIG. 6 is a right side view of the detachable sanitary handle for forearm lifting of refuse/recycle bin lids.

FIG. 7 is a top view of the detachable sanitary handle for forearm lifting of refuse/recycle bin lids; and,

FIG. 8 is a bottom view of the detachable sanitary handle for forearm lifting of refuse/recycle bin lids.

1 Claim, 8 Drawing Sheets
